UNITED STATES PATENT OFFICE.

WILLIAM J. MORAND, OF PASSAIC, NEW JERSEY, ASSIGNOR TO I. S. VAN DEUSEN & SON, OF SAME PLACE.

MACHINE FOR ROLLING BUTTONS ON WHIPS.

SPECIFICATION forming part of Letters Patent No. 271,503, dated January 30, 1883.

Application filed November 15, 1882. (No model.)

To all whom it may concern:

Be it known that I, WILLIAM J. MORAND, of Passaic, in the county of Passaic and State of New Jersey, have invented a new and useful Improvement in Machines for Rolling Buttons on Whips, of which the following is a full, clear, and exact description.

Reference is to be had to the accompanying drawings, forming a part of this specification, in which similar letters of reference indicate corresponding parts in all the figures.

Figure 1 is a plan view of my improvement. Fig. 2 is a sectional side elevation of the same, taken through the line *x x* of Fig. 1, and illustrating its use. Fig. 3 represents a part of a whip provided with two styles of buttons.

The object of this invention is to facilitate the rolling and finishing of the buttons on whips.

The invention consists in a machine for rolling buttons on whips, constructed with two parallel rollers provided with a driving mechanism, and a short roller pivoted to a swinging lever, whereby the said buttons can be readily rolled and finished while the whips and buttons are revolved by the said rollers, as will be hereinafter fully described.

A is the frame of the machine, which is designed to be secured to a suitable bench or frame, and to which are journaled two parallel rollers, *B C*. The rollers *B C* are placed at the same level, and to their ends are attached, or upon them are formed, two equal-sized gear-wheels, *D E*, the teeth of which mesh into the teeth of a gear-wheel, *F*, placed beneath them and journaled to the frame *A*.

The journal of the gear-wheel *F* projects at the outer side of the frame *A*, and is provided with a fast pulley, *G*, and a loose pulley, *H*, to receive the driving-belt, which belt is not shown in the drawings. The outer end of the journal of the gear-wheel *F* revolves in a bearing in a bracket, *I*, attached to the frame *A*. With this construction both the rollers *B C* will be revolved in the same direction.

Upon the rollers *B C*, and opposite each other, are formed grooves *J K* to give the de-

sired ornamental form to the buttons on the 50 whip.

To the rear part of the frame *A*, or to supports attached to the said frame, is journaled a shaft, *L*, to which is secured, by a set-screw or other suitable means, the end of a lever, *M*, to the side of which is pivoted a short roller, *N*, the face of which is grooved to correspond with the grooves *J K* of the rollers *B C*. The roller *N* is pivoted to the lever *M* in such a manner that when the said lever *M* is swung down the said roller *N* will be directly above the grooves *J K*.

Several sets of grooves of different forms can be made in the rollers *B C*, and several corresponding short rollers can be provided, 65 so that a roller can be pivoted to the lever *M* to correspond with any set of grooves in the rollers *B C*, the lever *M* being adjusted upon the shaft *L* in position to bring its roller over the set of grooves to be used.

A part of the rollers *B C* is left smooth for finishing smooth buttons, and a smooth roller, *O*, is pivoted to a lever, *P*, the end of which works loosely upon the shaft *L*, so that the said lever can be turned upon the 75 shaft *L* to tilt the said roller sufficiently to roll the ends of the button upon an inclination or bevel.

The roller *O* can be pivoted to the side of the lever *P*, or the said lever can be widened 80 and slotted to receive the said roller, as shown in Fig. 1.

In using the machine the whip is placed in the space between the rollers *B C*, with the button to be rolled over the grooves *J K*, or over the smooth parts of the said rollers, and the proper lever is swung down to bring its roller over the said button, and as the whip and button are revolved by the revolution of the rollers *B C* the desired form will be given 90 to the said button, the requisite pressure being applied by the operator with his hand.

Having thus fully described my invention, I claim as new and desire to secure by Letters Patent—

1. A machine for rolling buttons on whips, provided with the rollers *B C*, having a plain or smooth surface and corresponding grooved

surfaces, and with pivoted rollers N and O, with their swinging levers M P, substantially as and for the purpose set forth.

2. In a machine for rolling buttons on whips, the combination, with the two rollers B C, of the smooth roller O, pivoted to a swinging lever, P, substantially as herein shown and de-

scribed, whereby smooth buttons can be readily rolled and finished, as set forth.

WILLIAM J. MORAND.
